UNITED STATES PATENT OFFICE

ALRAH B. EDWARDS, OF CHICAGO, ILLINOIS

STENOGRAPHIC TYPEWRITING MACHINE

Application filed November 11, 1927. Serial No. 232,547.

This invention relates to stenographic typewriting machines and its principal object is to increase the number of letters and characters to be printed without increasing the number of keys, or shift keys, of a stenographic typewriting machine keyboard. 5

Another object is to provide simple and improved means for operably controlling the printing position of a striking mechanism to 10 provide increased character representation.

Another object of the invention is to provide novel means for increasing the number of letters and characters which may be written without the use of external shift keys, 15 and which will simplify the mental process of operating a machine keyboard by getting a direct representation of the letter or character without the necessity of using arbitrary code systems, code ciphers or a multiplicity 20 of double monogram type characters.

And another object of the invention is to provide novel means for operably connecting two or more striking mechanisms whereby 25 one striking mechanism will determine the printing operation of another striking mechanism and provide additional letters or characters.

In the accompanying drawings illustrating a selected embodiment of the invention 30 the views are as follows:

Fig. 1 is a detail plan view showing the position of the keys in relation to each other, and the normal position of the striking mechanisms, certain parts being broken away for 35 the sake of clearness.

Fig. 2 is a longitudinal sectional view taken on the line 2—2 of Fig. 1.

Fig. 3 is a face view of the various letters 40 and characters on the type bars to diagrammatically show the printing position of each letter or character against the platen roller.

Fig. 4 is a similar view showing the characters which are printed when the shift key 45 is used.

Fig. 5 is a face view of the letters on two striking type bars in their normal or idle position.

Figs. 6 to 10 are detail sectional views 50 showing the relative position of a pair of

striking mechanisms during the various printing operations. 55

Fig. 11 is a detail plan view similar to that shown in Fig. 1 embodying the invention in a modified form.

Fig. 12 is a longitudinal sectional view taken on the line 12—12 of Fig. 11.

Figs. 13 to 17 are detail sectional views showing the relative position of a pair of striking mechanisms during the various 60 printing operations.

Fig. 18 is a face view of the various letters and characters on the type bars to diagrammatically show the printing position of each letter or character against the platen roller. 65

Fig. 19 is a similar view showing the characters which are printed when the shift key is used.

Referring to Figs. 1 to 10 of the drawings 1 70 designates a striking mechanism and comprises the key lever 2, the key button 3 and the type bar or printing member 4 which carries the letters or characters 5.

A shift key 6 is operably connected to a type bar comb 7 to move all the type bars 4 75 which are pivotally connected at 8 to the key levers 2 to change the printing position of the type bars or printing members relative to the platen.

One of the type bars 4 is provided with 80 a pin 9 which is adapted to cooperate with, and slide in, a slot 10 formed in the next adjacent type bar 4' for operably connecting the two type bars together so that various letters can be printed according to the 85 movement of the key levers.

The type bar 4' is similar in all respects to the type bar 4 and merely carries this designating mark to distinguish one type bar from the other for descriptive purposes. 90

A key lever comb 11 supports the key levers to maintain them in proper alignment and a stop 12 arranged above the key levers limits their upward movement. A set screw 13 is provided to adjust the stop 12 for limiting the upward movement of the key levers. Suitable mechanism 14 comprising a fixed bar, a set screw, and a returning spring is provided to return the shift key and type bars to initial position. 95 100

In operation the striking mechanisms are in normal position as shown in Fig. 2. When it is desired to print the letter B on the type bar 4, for instance, pressure is borne down on the key button 3 of the key lever 2 which assumes the position shown in full lines in Fig. 6 thus causing the type bar 4 to strike the platen in its normal printing position. The pin 9 is free to travel in the slot 10 of the adjacent type bar 4' without shifting or moving the type bar 4', on its pivot 8. When it is desired to print the letter S which is positioned on the lower part of the adjacent type bar 4', Fig. 5, the key 3' is pressed downwardly causing the type bar 4', having the slot 10, to be shifted by the pin 9 on the type bar 4 into the position shown in Fig. 7. The pin and slot connection 9 and 10 between the type bars 4 and 4' merely acts to shift the printing position of the type bar 4' when the two type bars are moved relatively longitudinally by their respective key levers.

By pressing both of the key buttons 3 and 3' simultaneously as exemplified in full lines 25 in Fig. 8, both of the type bars 4 and 4' will move together toward striking position. This is due to the fact that type bar 4 carrying the pin 9 is not shifted relatively to the slotted type bar 4' hence both of the type 30 bars will move forwardly at the same time and at the same rate of speed. However, the single letter which is a combination of the letters G—J on the type bar 4' is made more than type high with respect to the letter B 35 on the adjacent type bar 4 so that it will project outwardly a little further than the letter B, thereby allowing only the combination character G—J to be printed. The pin 9 maintains its position in the slot 10, as 40 shown in Fig. 8. The letter B will be slightly removed from the platen as shown in Fig. 9 and the combination letter G—J will be in striking position against the platen as shown in Fig. 8. However, when both of the keys 45 3 and 3' are pressed, and the key button 3 is pressed slightly in advance of the key 3' as shown in Fig. 10, the type bar 4 will be slightly in advance of the type bar 4' which makes up for the prominence of the combination character G—J, and both the combination character and the character B will strike the platen simultaneously and print both the character B and the combination character G—J, Fig. 3. During this operation the pin 50 9 will move slightly longitudinally in the slot 10 as shown in Fig. 10 but will not cause the type bars to shift relatively to each other.

When the shift key 6 and the key 3 are simultaneously depressed or the shift key is 55 depressed and followed by the key 3, the type bar comb 7 moves all of the type bars forwardly on their pivots 8 relatively to the platen. Inasmuch as the type bar comb has shifted all of the type bars to a forward position the letter B on type bar 4 will be out

of printing position with respect to the platen and the figure 1 will be in printing contact as shown in Fig. 4, thus enabling the character 1 to be obtained with the same striking mechanisms.

If the shift key 6 and both keys 3, 3' are all depressed simultaneously or the shift key depressed and followed by the simultaneous depression of both keys 3, 3' the figure 1 and the letter S will print as shown in Figs. 4 and 75 10 thus enabling a different combination of printed characters to be obtained.

By operatively interconnecting the two type bars or printing members thereby causing one to shift relatively to the other, more letters can be printed with a given number of keys than heretofore known to be printed 30 in machines of this character.

In Figs. 11 to 19 which is a selected embodiment of the invention in a modified form 35 20 designates a striking mechanism comprising the key lever 21, key button 22, and type bar 23 which is operated through an intermediate link 24. A shift key 25 operatively connected to a type bar comb 26 shifts all the type bars in relation to the platen 27 in a manner well known in the art. A universal bar 28 is adapted to operate the platen roller 27, Fig. 12, and a stop bar 29 limits the upward movement of the key levers. The type 40 bar 23 of the striking mechanism 20 is provided with a pin 30 which is adapted to engage a slot 31 in the adjacent type bar 23' which is an operative part of the striking mechanism 20'. Suitable mechanism 33 and 34, Fig. 12, is operably connected to the key lever and type bar to return the same to initial 45 position.

The striking mechanisms are in their normal position as shown in Fig. 12 and for the purpose of illustration the same printing characters will be used for reference as employed in explaining the device shown in Figs. 1 to 10. When it is desired to print the letter B the button 22 is pressed as shown 50 in full lines in Fig. 13 allowing the type bar 23 to move forward to normal printing position; the pin 30 is free to move its required distance in the slot 31 without in any way affecting or shifting the type bar 23'. The type bar 23 will move inwardly in normal printing position as shown in Fig. 13 and the letter B will be printed, Fig. 18.

When the key button 22' is pressed to operate the type bar 23' this type bar will move to the position shown in Fig. 14. As this type bar carrying the lower letter S is being guided by the pin 30 on the type bar 23 the type bar 23' will be raised and cause the letter S on the lower part of the type bar 110 115 23' to be printed.

When both of the striking mechanisms 20 and 20' are operated simultaneously as shown in full lines in Fig. 15 the type bars 23 and 23' of each mechanism will move together 120 125

evenly, thereby preventing the type bar 23' from being operated by the pin 30, as both of the type bars are moving forward at the same rate of speed. This movement would normally cause both of the upper characters on each of the type bars to be printed, but as the single combination character G-J is more prominent than the letter B only the combination character G-J will be printed. The type bar 23' carrying the character G-J will be against the platen as shown in Fig. 15 while the type bar 23 will be in the position shown in Fig. 16 with the letter B away from the platen and therefore not printed. If both the character B and the combination character G-J are desired to be printed at the same time, the striking mechanisms 20 and 20' are both operated with accent on the striking mechanism 20 and the key levers of each striking mechanism will be in the position shown in Fig. 17. This will cause the type bar 23 of each striking mechanism to be moved slightly in advance of the type bar 23' of the other striking mechanism and bring the face of both the character B and the combination character G-J in alignment so that both of these characters strike the platen simultaneously and are printed.

By pressing the shift key 25, Fig. 12, the type bar comb 26 will cause the type bars of all the striking mechanisms to be moved on their axes 32 thereby shifting the relative position of the characters in relation to their former or normal printing position on the platen. When the striking mechanism 20 is depressed its type bar 23 will move forward as formerly, but the bottom portion of this type bar carrying the figure 1 will print; the letter B being raised from its normal printing position. If the shift key and both of the striking mechanisms are depressed simultaneously both of the bottom characters of the respective striking mechanisms will be printed due to the new printing position caused by the operation of the type bar comb, Fig. 19.

While I have shown the type bars interconnected with a pin and slot arrangement, it is to be understood that a similar arrangement may be made with the key levers; or instead of just having two characters on each type bar, more may be employed, and the arrangement of the slot and pin changed to cause more than two letters to be printed from the same type bar.

Changes may be made in the form, construction and arrangement of the parts without departing from the spirit of the invention or sacrificing any of its advantages and the right is hereby reserved to make all such changes as fairly fall within the scope of the following claims:

I claim:

1. In a machine of the class described provided with type bars having printing char-

acters, a platen, key buttons for operating said bars, and means connecting a pair of said bars for obtaining an imprint from an elevated character on a single type bar by pressing a pair of key buttons.

2. In a machine of the class described provided with type bars having a plurality of printing characters, key buttons for operating said bars, means connecting a pair of said bars for selectively obtaining different characters or combination of characters as contained on two of said type bars by alternately and simultaneously operating the bars of said pair.

3. In a machine of the class described provided with type bars, a platen a pair of characters on each of said bars and disposed one above the other, keys for operating said bars, means connecting a pair of said type bars for causing the lower character of one bar of said pair to be brought to printing position relative to the platen by directly pressing one key and for causing the upper character of the other type bar of said pair to be brought to printing position relative to the platen by directly pressing another key.

4. The combination in a stenographic typewriting machine of a platen and a plurality of type bars, a plurality of printing characters on each type bar and disposed relatively close to the platen, of a pin on one of said bars and adapted to engage a slot in another of said bars for guiding one bar relative to the other bar to shift said bar relative to the platen to cause a plurality of different characters on said bars to be brought to printing position relative to the platen upon operation of either of said last named type bars.

5. In a machine of the class described, a striking mechanism having printing characters and adapted when operated to print one of its said characters, a second striking mechanism having printing characters and adapted when operated to print one of its characters, and means interconnecting said mechanisms whereby simultaneous operation of the interconnected mechanism will print an elevated character on one of the mechanisms.

6. In a machine of the class described, a plurality of striking mechanisms each having a plurality of printing characters and adapted when individually operated to print a different character, and means responsive to the simultaneous operation of said mechanisms for causing them to print an elevated character on one mechanism different from the character printed by the individual operation of said mechanisms.

7. In a machine of the class described the combination of a pair of striking mechanisms each having a pair of printing characters and adapted when individually operated to print one of their characters, means respon-

sive to the simultaneous operation of both of said mechanisms for causing them to print an elevated character of one of the pair of characters on the first of the mechanisms different from the characters printed by the individual operation of said mechanisms, and means operable with one of said mechanisms for printing the other character of the pair of characters on the second mechanism when said mechanism is operated independently of the first mechanism and with said means operable therewith.

8. In a machine of the class described provided with striking mechanisms, a platen, a pair of characters on each of said mechanisms and spaced one above the other, means interconnecting a pair of said mechanisms for causing the top character of one mechanism to be brought to printing position by directly operating said mechanism, and for causing the lower character on the other mechanism to be brought to printing position relative to said platen by directly operating said other mechanism.

25 9. In a machine of the class described, a platen, a plurality of striking mechanisms each having printing characters and a pin on one of said mechanisms adapted to engage a slot in another of said mechanisms, said pin and slot being arranged to shift one or the other of said mechanisms relatively to the platen when the mechanisms are individually operated to bring different characters on said mechanisms to printing position.

35 10. In a machine of the class described the combination of a platen, a pair of key levers, a type bar operated by each lever having a plurality of printing characters thereon, and means on said type bars for shifting one type bar relatively to the platen when the key therefor is operated.

40 11. In a machine of the class described the combination of a platen, a pair of key levers, a type bar operated by each lever having a plurality of printing characters thereon, means on said type bars for shifting one type bar relatively to the platen when the key therefor is operated, and a shifting device for shifting both of said type bars relatively to the platen.

45 12. In a machine of the class described the combination of a platen, a plurality of type bars each having printing characters thereon, individual key levers for actuating said type bars and adapted when operated simultaneously to move said type bars together into printing relation to the platen, and means for shifting the type bars relatively to each other when a key lever is individually operated to bring a different character into printing relation to the platen.

50 13. In a machine of the class described the combination of a platen, a plurality of type bars each having printing characters thereon, individual key levers for actuating said

type bars and adapted when operated simultaneously to move said type bars together into printing relation to the platen, means for shifting the type bars relatively to each other when a key lever is individually operated to bring a different character into printing relation to the platen, and a shifting key lever for shifting all of said type bars relatively to the platen.

55 14. In a machine of the class described the combination of a platen, a pair of levers, a type bar pivotally mounted on each lever and having a plurality of printing characters and adapted when both levers are simultaneously actuated to move together into printing relation to the platen, means interconnecting said type bars and adapted when one of said levers is actuated to swing the type bar for the other lever on its pivot relatively to the platen, a type bar comb common to all of said type bars for shifting the type bars on their pivots relatively to the platen, and a shift key for actuating said type bar comb.
